AUTOMATIC BIRD FEEDER

Aubrey L. Morrow, 124 Pithon St.,
Lake Charles, La. 70601

Filed Nov. 12, 1968, Ser. No. 14,396

Term of patent 14 years

Int. Cl. D30—02

U.S. Cl. D30—15

FIG-1

FIG-2

FIG. 1 is an elevational view of an automatic bird feeder, showing my new design, and

FIG. 2 is a top perspective view thereof.

The rear half of the bird feeder is identical to that shown in the drawing figure.

I claim:

The ornamental design for an automatic bird feeder, substantially as shown and described.
